UNITED STATES PATENT OFFICE.

FRANK M. BURROWES, OF PORTLAND, MAINE.

TOY BUILDING-BLOCKS.

1,009,469.

Specification of Letters Patent. Patented Nov. 21, 1911.

Application filed March 7, 1911. Serial No. 612,829.

To all whom it may concern:

Be it known that I, FRANK M. BURROWES, a citizen of the United States, residing at Portland, in the county of Cumberland and State of Maine, have invented certain new and useful Improvements in Toy Building-Blocks, of which the following is a specification, reference being had therein to the accompanying drawing.

10 This invention relates to improvements in toy building blocks and has for its primary object the provision of a plurality of blocks adapted to interfit one with another and to prevent relative movement of the adjacent blocks in any direction laterally of the blocks when assembled. Heretofore in this art, building blocks have been provided with complementary tongue and groove portions adapted to coöperate to prevent relative movement of adjacent blocks transversely of the tongue and groove, but no provision was made to prevent relative movement lengthwise of the tongue and groove. With this in mind, the present invention embodies as 25 a salient characteristic, means enabling the utilization of the tongue and groove idea, while at the same time operating to prevent said longitudinal displacement of the assembled blocks. The advantages of this advanced step in the art will be readily apparent, but it may be here noted that the improvements will be helpful in a great measure, in producing structural formations from the blocks, by reason of the fact that 35 when a block is placed in position in a predetermined coöperation with adjoining blocks, the same will be positively maintained against displacement, save by an intentional lifting or removing operation.

40 To the ends stated, a convenient embodiment of the invention comprises superposed blocks, the abutting surfaces of which are formed with a coöperating tongue and groove, and the tongued and grooved portions being also formed to interlock to prevent relative movement of the blocks longitudinally of the tongue. Conveniently, the latter is accomplished by recessing the tongue and providing a dowel or projection 50 in the groove adapted to fit said recess, the same idea being carried forward in such instances as where longitudinal and transverse grooves are formed in a block by positioning the projection or dowel at the point of 55 intersection of said grooves, whereby the blocks may be arranged either in parallel or

in angular relation and in either position effectually secured against any relative lateral or horizontal play or disarrangement.

The details in the construction and arrangement of parts will be clear from the specific description hereinafter contained, when read in connection with the accompanying drawings forming part hereof and wherein, for the sake of illustration, I have 60 illustrated the preferred embodiment of the invention, but in this connection it will be understood by those skilled in the art that the invention is capable of embodiment in 65 other forms and devices.

In the drawings, Figure 1 is a perspective view of one of the blocks, Fig. 2 is a similar view of the block in another position, Fig. 3 is a face view of a pair of the blocks in superposed relation, Fig. 4 is a similar view 75 of three of the blocks in overlapped or staggered relation, Fig. 5 is a vertical sectional view through Fig. 4, Fig. 6 is an elevation of two of the blocks arranged to form a corner, that is, with the blocks at right angles to, 80 each other, Fig. 7 is a horizontal section through Fig. 4 on line α — α ; and Fig. 8 is a sectional view of the construction shown in Fig. 6.

Referring more specifically to the drawings, wherein like reference characters designate corresponding features in the several views, A represents the body of the block conveniently of oblong formation in simulation of a brick, the opposite faces and ends 90 of which are plain, as shown. On the top B of the block, I provide a centrally arranged longitudinal rib or tongue, the tongue in turn being cut away or recessed as at D near the opposite ends of the block, 95 for a purpose as will presently appear.

The bottom E of the block is formed with a complementary centrally arranged longitudinally extending groove F and one or more similar transverse grooves G intersecting said groove F. In the groove F and at points directly beneath the apertures D, I provide projections or dowels H, it being observed that one of these dowels is arranged at the point of intersection of the 105 grooves F and G.

The block is formed of a length approximately twice its width and the recesses D and dowels or projections H are arranged at points away from the ends of the block 110 a distance approximately equal to one-fourth of the length of the block, so that

superposed blocks may be arranged in true parallel relation to form a flat wall or in right angular relation to form a corner, as is obvious. When the blocks are assembled, 5 it is clear that the interfitting tongues C and grooves F will insure proper seating of the upper block upon the lower and prevent relative movement transversely of the block, while the interfitting of the projections H 10 with the recesses D will also prevent relative longitudinal or endwise movement of said blocks, the arrangement of these last mentioned elements accomplishing the results stated, whether the blocks are parallel or in 15 angular relation.

As a satisfactory practical proposition, the projections or dowels H are constituted by recessing the base of the groove F and the insertion of close fitting projecting plugs 20 therein secured by frictional engagement or glued, if desired, the lower ends of the projecting portions of the blocks terminating within the plane of the bottom E of the block.

25 I claim:

1. A block of the character described provided on one surface with a tongue and on its opposite surface with a groove, the tongue being recessed at a point intermediate of its ends, and a projection being provided in the groove, substantially as and for the purpose described.

2. A block of the character described provided on one surface with a tongue and on 35 its opposite surface with intersecting groove portions, the tongue being recessed at a point intermediate of its ends, and a projection being provided at the point of intersection of the grooves, substantially as and 40 for the purpose described.

3. A block of the character described provided on one surface with a tongue and on its opposite surface with a groove, the tongue being recessed at separated points

and similarly separated projections being 45 provided in the groove, substantially as and for the purpose described.

4. A block of the character described provided on one surface with a tongue and on its opposite surface with intersecting 50 grooved portions, the tongue being recessed at separated points and similarly separated projections being provided in the grooved portions, one of said projections being at the point of intersection of the grooves, substantially as and for the purpose described. 55

5. A block of the character described provided on one surface with a tongue and on its opposite surface with a plurality of intersecting grooved portions, the tongue being recessed at separated points and similarly separated projections being provided in the grooved portions arranged at the points of intersection of grooved portions, substantially as and for the purpose de- 60 scribed. 65

6. A set of building blocks of the character described provided with interfitting tongue and groove portions at their meeting edges, the tongue portion being recessed and 70 the grooved portion being provided with a projection adapted to engage the recess, substantially as and for the purpose described.

7. A set of building blocks of the character described provided with interfitting 75 tongue and groove portions at their meeting edges, the grooved portions also having intersecting grooves and projections arranged at the points of intersection of the grooves, and the tongue portions being recessed to 80 receive said projections, substantially as and for the purpose described.

In testimony whereof I affix my signature in presence of two witnesses.

FRANK M. BURROWES.
